His Attorney

UNITED STATES PATENT OFFICE.

DANIEL G. SELL, OF KANSAS CITY, MISSOURI.

TROUSERS HANGER AND PRESSER.

1,356,093.

Specification of Letters Patent. Patented Oct. 19, 1920.

Application filed July 5, 1919. Serial No. 308,878.

To all whom it may concern:
Be it known that I, DANIEL G. SELL, a citizen of the United States, residing at Kansas City, in the county of Jackson and 5 State of Missouri, have invented a certain new and useful Improvement in Trouser-Hangers and Pressers, of which the following is a specification.

My invention relates to improvements in 10 trouser-hangers and pressers.

The object of my invention is to provide a novel, simple, cheap, easily operated and efficient trouser hanger and presser.

The novel features of my invention are 15 hereinafter fully described and claimed.

In the accompanying drawing, which illustrates the preferred embodiment of my invention,

Figure 1 is a perspective view of my im- 20 proved trouser hanger and presser, the parts being shown disassembled.

Fig. 2 is a side elevation of my improved trouser presser and hanger shown mounted in operative position on a pair of trousers.

25 Fig. 3 is a vertical sectional view on the line 3—3 of Fig. 2.

Fig. 4 is an enlarged cross section on the line 4—4 of Fig. 2.

Similar reference characters designate 30 similar parts in the different views.

1 designates a transverse bar, preferably cylindrical, over which the trousers 2 are adapted to be folded and suspended.

3 and 4 designate respectively two flat 35 clamping members, which may be of sheet metal, wood, fiber, paste-board or other suitable material. The trousers 2 are adapted to be clamped between the members 3 and 4.

40 Between the members 3 and 4 is a flat member 5, which may be of material similar to that of which the members 3 and 4 are composed. The flat member 5 is intermediate of the members 3 and 4 and is adapted 45 to have the trousers 2 folded over it, as best shown in Figs. 3 and 4.

For holding the members 3, 4 and 5 in the clamping position shown in Figs. 2, 3 and 4, suitable releasable means may be provided. For this purpose, I have provided 50 two channel members 6, which may be more or less resilient and which are adapted to releasably engage opposite edges of the

members 3, 4 and 5, for holding the latter in the clamping position. 55

In order that the hanger and presser may be suspended, suitable means may be provided.

For this purpose, in the form of my invention shown in the drawing, for supporting the bar 1, I provide a cord 7, the ends of which are respectively secured to the ends of the bar 1. The cord 7 is adapted to be slipped over and supported by a suitable supporting device, such as a suitably supported nail 8. 60

For supporting the intermediate member 5, I provide two cords 9 attached respectively to the ends of the bar 1 and attached to the member 5 adjacent to the two upper 70 corners respectively of the member 5.

For supporting the members 3 and 4, I provide two cords 10 and 11, which are adapted to be supported by the nail 8. The cord 10 has its ends attached to the member 3 adjacent to the upper edge of the latter, and the cord 11 has its ends attached to the member 4 adjacent to the upper edge of the latter. 75

In the operation of my device, the trousers 2 are slipped between the cord 7 and bar 1 and folded over the bar and the intermediate member 5, as shown in Figs. 2 and 3. The members 3 and 4 are then pressed against opposite sides of the trousers, after 80 which the channel members 6 are slipped onto the opposite side edges of the members 3, 4 and 5. The width of each channel member 6 between its flanges is such that the clamping members 3 and 4 will be squeezed 85 tightly against the trousers, the expansive force of which will hold the channel members on the clamping members. The hanger may then be supported on the nail 8 by 90 means of the cords 7, 10 and 11. 95

I do not limit my invention to the structure shown and described, as modifications, within the scope of the appended claims, may be made without departing from the spirit of my invention. 100

What I claim is:—

In a trousers hanger and presser, a transverse bar adapted to have the trousers folded over it, three flat pressing members, two cords supported by the bar and supporting 105 one of the pressing members adjacent to its

side edges, two cords respectively supporting the other two pressing members, and a cord supporting the bar, the three last named cords being adapted to be supported by a nail or a similar device, with the upper edges of the pressing members in substantially the same horizontal plane, the pressing members having a greater width than

the width of the trousers adapted to be pressed between them, and clamping means 10 for releasably engaging opposite side edges of the pressing member, substantially as set forth.

In testimony whereof I have signed my name to this specification.

DANIEL G. SELL.
